No. 18445.

Patented Oct 20, 1857.

— FIG. 1. —

— FIG. 3. —

— FIG. 2. —

UNITED STATES PATENT OFFICE.

BENJAMIN F. GRINNELL, OF NEW YORK, N. Y.

WRISTBAND-FASTENER.

Specification of Letters Patent No. 18,445, dated October 20, 1857.

To all whom it may concern:

Be it known that I, BENJAMIN F. GRINNELL, of the city of New York and State of New York, have invented a new and useful 5 Improvement in Wristband-Fasteners; and I do hereby declare that the following is a full, clear, and exact description of the same, reference being had to the accompanying drawing and to the letters of reference 10 marked thereon.

My invention consists in a combination of metallic plates, springs, and connections, fully described hereafter and so arranged and constructed as to form fasteners for 15 wristbands, which when secured in their proper positions, have little or no liability to become detached and lost.

On reference to the drawing which forms a part of this specification, Figure 1 is an 20 external plan, showing my improved fastener as attached to the wristband. Fig. 2, an internal plan of the same, and Fig. 3, an end view.

The above views are drawn to a scale of 25 three times their actual size, and the same letters of reference allude to similar parts throughout the drawing.

A, A' are the two ends of a wristband furnished with the usual button holes a 30 and a'.

B is the external plate or shield of the fastener, which may be engraved, or otherwise ornamented with any suitable device, or be inlaid with cameos, or fancy stones; 35 this plate is connected by means of metal strips d, d', to the lower buttons e and e'. To the button e' is soldered or otherwise secured a metallic spring f the end of which

bears against the face of the button e. The fastener thus constructed is attached to the 40 end A' of the wristband by sliding the outside end of the button hole between the spring f and the button e, and afterward drawing it in the direction of the arrow (Fig. 3) when the sides of the button hole 45 may be easily expanded, so that the end A' of the wristband may assume the position shown in Fig. 3, that is with the button hole surrounding the connecting strip d', between the external plate B and button e'. 50 The other end A of the wristband is then passed between the spring f, and button e, the edges of the button hole expanded, and passed over the said button, so as to surround the connection d, thus connecting the 55 two ends of the wristband together.

Should the end A of the wristband escape from its fastening, it would be next to an impossibility, on account of the spring f, for the other end to escape, and thus the 60 loss of fasteners, common to those of ordinary construction is avoided.

What I claim and desire to secure by Letters Patent is—

The external plate B, with its connections d and d' and buttons e and e', in combination with the spring f, the whole being constructed substantially in the manner and for the purpose specified.

In testimony whereof I have signed my 70 name to this specification before two subscribing witnesses.

B. F. GRINNELL.

Witnesses:

WILLIAM E. WALTON,
T. P. McDONOUGH.
